C. J. TRAVERS.

ADJUSTMENT FOR THE BACKS OF TYPE WRITER CHAIRS.

APPLICATION FILED OCT. 11, 1917.

1,263,161.

Patented Apr. 16, 1918.

Inventor:

Chas. J. Travers,
by W. C. Duval,
Attorney.

UNITED STATES PATENT OFFICE.

CHARLES J. TRAVERS, OF PORT WASHINGTON, WISCONSIN, ASSIGNOR TO GILSON MANUFACTURING CO., A CORPORATION OF WISCONSIN.

ADJUSTMENT FOR THE BACKS OF TYPE-WRITER CHAIRS.

1,263,161.

Specification of Letters Patent. Patented Apr. 16, 1918.

Application filed October 11, 1917. Serial No. 195,875.

To all whom it may concern:

Be it known that I, CHARLES J. TRAVERS, a citizen of the United States, residing at Port Washington, in the county of Ozaukee 5 and State of Wisconsin, have invented new and useful Improvements in Adjustments for the Backs of Type-Writer Chairs, of which the following is a specification.

This invention relates to adjustments for 10 chairs, and has special reference to such as are employed in connection with the backs of type-writer and sewing-chairs, wherein, as is well known, the back-pads are generally adjustable at the upper ends of the 15 supporting-standards and the latter pivotally and yieldably supported at their lower ends, all of which tend to lend comfort and ease to the chair-occupant.

The principal objects of my present invention 20 are to produce an adjustment of the class described which, for the most part, is capable of being constructed of sheet-metal, and hence cheapened in manufacture; which is rigid and durable in use; the adjustment 25 of whose parts may be accomplished by the occupant from the seat; and wherein the back-pad may be rigidly attached, if desired to the back-standard, and yet is capable of ready adjustment; and, furthermore, where- 30 in may be omitted the means usually employed for adjusting the back-pad.

Other objects and advantages of the invention will hereinafter appear, and the novel features thereof will be particularly 35 pointed out in the appended claims.

Referring to the drawing—

Figure 1 is a plan view of an adjustment embodying my improvements, the back-supporting standard and the arms supporting 40 the same being shown in section; and

Fig. 2 is a vertical longitudinal sectional view of the adjustment, the nearest back-standard supporting-arm being shown in side elevation and the back-standard being 45 broken away above the same.

Similar numerals of reference indicate similar parts in all the figures of the drawing.

In practice, I employ the usual sheet- 50 metal spider-arms 1, formed of angle-iron, the same having their upper horizontal flanges outwardly disposed and provided near their outer ends with perforations 2, through which, it will be understood, are

upwardly inserted the screws (not shown) 55 by which the chair-seat is secured in place.

These spider-arms, in this instance, are connected near their rear ends by a sheet-metal cross-brace 3, the opposite ends of the brace being downwardly bent and secured, 60 preferably by rivets 4, to the inner sides of the vertical flanges of the arms.

Loosely suspended from a central aperture formed in the cross-brace is an adjusting-bolt 5, upon the lower end of which 65 is threaded an adjustable hand-wheel 6, that supports a washer 7, the latter, at diametrically opposite points, being upwardly bent, as at 7^a.

At a suitable distance in advance of the 70 cross-brace 3, a transverse bolt 8, connects the opposite vertical flanges of the spider-arms 1, and pivoted upon the latter, so as to be capable of vertical movement at their 75 rear ends, is a pair of back-standard supporting-arms 9, the same being, in this instance, of uniform width, and, therefore, formed of ordinary blanks of sheet-metal. In rear of the spider-arms, the supporting-arms 9 converge, as shown, for the purpose 80 of embracing the back-standard, as herein-after described.

A spacing-sleeve 10, is preferably mounted on the bolt 8, and is interposed between the supporting-arms 9, whereby the latter 85 are retained in proper spaced relation with each other, the rear portions of the arms being maintained in like spaced relation by a transverse spacing-plate 27, the opposite ends of which are downwardly disposed 90 (see dotted lines Fig. 2) and riveted, as at 27^a, to said arms 9. The spacing-plate 27 is provided with an aperture 27^b, to permit of the passage therethrough of the adjusting-bolt 5, the aperture being somewhat 95 larger than the bolt, so that the bolt may always remain substantially vertical.

A pair of coiled-springs 11, are mounted upon the sleeve 10, the upper terminals 12, of the springs engaging under the trans- 100 verse spacing-plate 27, at opposite sides of the bolt 5, and the lower terminals 13, of the springs resting upon the washer 7, and retained in position thereon and at opposite sides of the bolt 5, by the upturned 105 or flanged sides 7^a thereof.

The springs, it will be observed, yieldingly support the arms 9, the tension of the

5 springs being readily increased or diminished by a manipulation of the hand-wheel 6, through which the terminals of the springs may be adjusted toward or away from each other.

14 designates the back-supporting standard, which, it will be understood, carries the usual back-pad (not shown) at its upper end. To give to this back-pad the desired 10 adjustability, it is usual to slot the upper end of the standard and connect the pad to the standard by means of an adjusting-bolt carrying a hand-wheel, the latter projecting outwardly at the back of the standard. This 15 wheel is not only unsightly, but forms a projection upon which the clothing of the user of the chair is apt to catch and tear, so that it is highly desirable to obviate the use of this form of adjustment. In the present instance, therefore, it will be understood that 20 I secure the back-pad rigidly in position upon the supporting-standard 14, and hence omit the unsightly and undesirable hand-wheel for adjusting and securing the same 25 in position. At the same time, however, it will be apparent, I yet secure the adjustable feature of the back-pad but do so through the standard itself.

Any desirable means may be employed 30 for pivotally mounting the back-standard 14 at its front edge between the standard-supporting arms 9, one very simple means being illustrated wherein the arms 9 have punched inwardly therefrom at opposite 35 points, rounded lugs 15, the latter engaging corresponding bearing-recesses 16, formed in the opposite sides of the standard. Upon these lugs the standard 14 is capable of swinging back and forth, as will be obvious. 40 The arms 9 may be provided with curved slots 19, and a corresponding though preferably somewhat longer slot 20, may register with the slots 19 and be formed in the back-standard 14, near the lower end of the latter, 45 the two sets of slots being concentric with the bearing-lugs 15. Through the slots 19 and 20, is passed a transverse clamping-bolt 21, at one end of which is the usual head and at the other a hand-wheel 23. It is 50 usual, in instances of this kind, to slot the arms 9, and, in order that said slots may be of sufficient length to give the standard proper adjustability, said arms 9 are generally flared or widened at their rear ends. 55 By this arrangement described, the arms 9 may be formed of a strip of metal of uniform width and the slots 19 made shorter than usual and within the confines of the arms, the adjustability desired being secured 60 by reason of the presence of the slot 20 in the standard.

It will be understood, of course, that the adjustment is permanently mounted at the upper end of the usual adjusting-standard 65 26, these two parts being secured to each

other in any desired and well-known manner. In the present instance, however, I employ a tubular transverse bridge 25, the same being preferable by reason of its lightness, strength, and rigidity. The ends of 70 the bridge-piece may be provided with tenons 28, let into the corresponding openings or mortises 29 formed in the vertical flanges of the spider-arms 1, the ends of the tenons being headed. In this manner the spider- 75 arms are rigidly connected and cannot work loose as if these parts were merely riveted together. The bridge-piece, it will be understood, is provided with upper and lower alining openings 30, and these receive the 80 upper reduced end 31 of the adjusting-standard, the latter being headed or upset above the bridge.

It will be obvious that by pivoting the arms 9 at their front ends and having them 85 under the tension of the two springs 11, said arms, and, consequently, the back-standard 14 together with the back-pad carried thereby, will yieldingly resist the body-pressure exerted by the occupant of the 90 chair, so that the back of the occupant is at all times comfortably supported. The amount of resistance to the body-pressure may be conveniently regulated by the hand-wheel 6, the latter being within easy reach 95 of the occupant. Thus, by rotating the wheel so that it is run upwardly upon the bolt 5, the tension of the springs 11, and, hence, the yielding support of the arms 9, will be increased, as the terminals of the 100 springs will be thereby forced toward each other, and by a reverse rotation of the hand-wheel, the terminals of the springs will be permitted to expand so that the coils will be under somewhat less tension. The occupant may also raise, lower, and incline the back-standard to suit his comfort and taste by loosening the hand-wheel 23, adjusting the parts the desired degree, and subsequently retightening the hand-wheel so that 105 it causes the rear ends of the arms 9 to clamp and hold the back-standard at the desired point of adjustability.

Having described my invention, what I claim is:

1. The combination, in a chair-iron, with a pair of rearwardly disposed pivoted arms provided near their rear ends with curved parallel companion slots, and in advance of the same with inwardly punched rearwardly disposed rounded bearing-tongues concentric with the slots, of a back-supporting standard embraced by said arms and having a transverse bearing at its front edge pivotally engaging said tongues, a 115 clamping-bolt passed through the slots of the arms and through the standard, and a hand-wheel threaded on one end of the bolt.

2. The combination, in a chair-iron, with a pair of rearwardly disposed pivoted arms 120

provided near their rear ends with curved parallel companion slots, and in advance of the same with inwardly punched rearwardly disposed rounded bearing-tongues, 5 of a back-supporting standard embraced by said arms and provided with a transverse bearing-recess at its front edge pivotally engaging said tongues and in rear thereof having a concentric slot corresponding 10 to the slots of the arms, a clamping-bolt passed through the slots of the arms and of the standard, and a hand-wheel threaded on one end of the bolt.

3. The combination, in a chair-iron, with 15 a pair of pivotally supported rearwardly disposed arms, means for yieldingly pressing the same upward, opposite bearing-tongues punched inwardly from said arms and offset therefrom, of a back-supporting 20 standard having a transverse bearing at its front edge pivotally mounted to rock on said arms, and means for securing said standard in adjusted relation with said arms.

4. The combination, in a chair-iron, with 25 a pair of rearwardly disposed back-standard supporting-arms, a back-standard embraced by said arms, and means for securing the standard in adjusted relation with said arms, of a transverse pivotal support 30 for the front ends of the arms, a pair of spider-arms paralleling the supporting-arms, a transverse-brace connecting the spider-arms, a tension-bolt depending from the brace, a spacing-plate connecting the 35 supporting-arms, a hand-wheel threaded on the lower end of the tension-bolt, a washer upon the bolt above the hand-wheel, and a pair of springs coiled about the pivot of the arms and having their upper and lower terminals 40 engaging the transverse brace and the washer respectively.

5. The combination, in a chair-iron, with a pair of spider-arms formed of angle-iron, a transverse brace connecting the vertical

flanges of the same, a transverse bolt connecting the flanges in rear of the brace, a pair of back-standard supporting-arms pivoted at their front ends upon the bolt between the spider-arms, a spacing-sleeve mounted on the bolt and interposed between 45 the said supporting-arms, and a spacing-plate connecting the supporting-arms, of a back-standard adjustably mounted between the latter arms, a tension-bolt depending through an opening formed in the transverse brace between the supporting-arms, and passing through an aperture in the spacing-plate, a hand-wheel threaded on the lower end of the bolt, a washer carried by the bolt, and a pair of springs coiled at 50 their centers about the spacing-sleeve and having their upper and lower terminals respectively engaged by the said brace and washer.

6. The combination, in a chair-iron, with 55 a pair of rearwardly disposed sheet-metal arms provided with inwardly punched bearing-tongues, of a back-supporting standard having one of its edges grooved to receive said bearing-tongues, whereby said 60 standard becomes pivotally mounted between the said arms, and means for securing said back-standard in its adjusted pivoted relation with said arms.

7. The combination, in a chair-iron, with 70 a pair of rearwardly disposed sheet-metal arms provided with inwardly punched bearing-tongues, of a back-supporting standard having opposite bearing-recesses to receive said tongues, whereby said standard 75 becomes pivotally mounted between said arms, and means for securing said back-standard in its adjusted pivoted relation with said arms.
